CLAIM

The ornamental design for an outdoor luminaire, as shown and described.

DESCRIPTION

FIG. 1 is a front perspective view of an outdoor luminaire showing our new design;
FIG. 2 is a rear view thereof;
FIG. 3 is a top view thereof;
FIG. 4 is a right side view thereof;
FIG. 5 is a left side perspective view thereof; and,
FIG. 6 is a front view thereof.

(Continued)

The broken lines show portions of the outdoor luminaire that form no part of the claimed design.

1 Claim, 3 Drawing Sheets
